SWAB FOR FINGER HOLES OF BOWLING BALLS OR THE LIKE

Paul R. Koontz, Sr., 5617 E. 40th St.,
Kansas City, Mo. 64130

Filed Apr. 29, 1966, Ser. No. 2,061

Term of patent 3½ years

(Cl. D9—2)

Fig.2.

Fig.3.

Fig.1.

FIG. 1 is a side elevational view of a swab for finger holes of bowling balls or the like, showing my new design;

FIG. 2 is a top plan view thereof; and

FIG. 3 is a bottom plan view thereof.

The side not shown has substantially the same appearance as the side shown.

I claim:

The ornamental design for a swab for finger holes of bowling balls or the like, as shown and described.
